UNITED STATES PATENT OFFICE

LEON THIRY, OF HUY, BELGIUM

METHOD OF AND APPARATUS FOR PRODUCING FLEXIBLE BEARING BLOCKS

Application filed April 24, 1930, Serial No. 446,926, and in France April 26, 1929.

This invention relates to a method of and apparatus for producing flexible bearing blocks suitable for use as fixed supports or as joints between relatively movable elements.

5 The invention has particular reference to a method of connecting two elements arranged one within the other by means of a third element, namely, an elastic substance interposed between the two first elements, the elastic substance having been first deformed with respect to its initial dimensions.

Briefly, the invention comprehends a condition in the manufacture of bearing blocks of this character, wherein a deformation of 15 the elastic substance is produced by means of a more or less pronounced elongation of the substance, a step which may be accomplished for example by means of compression, the latter being obtained by compressing or pressing 20 back the elastic material in a space having dimensions which correspond to the desired deformation.

The products of my invention are suitable 25 for fixed supports or as joints for articulations of oscillating parts and are especially applicable as pivot or swivel joints, in the latter case the elongation of the elastic substance is effected in the direction of the axis of oscillation.

30 The two nested elements, mentioned in the foregoing paragraphs, may be constructed of any material, but it is preferable that they be of metal. The transverse section of the space between the two metal elements occupied by the intermediate elastic substance may take 35 any form or dimension; however, it has been found that a circular formation is preferable. As to the longitudinal section of the intervening space and its elastic element, it too may be of almost any desired formation although a cylindrical or conical shape is the most desirable.

I carry out my improved method of producing resilient bearing blocks by means of 40 a plurality of steps which, in practice, are

performed by a type of apparatus of which several embodiments are illustratively exemplified in the accompanying drawings.

Before proceeding with a description of the apparatus by means of which the invention is practiced, it should be explained as a matter of information that at the time of the elongation of the elastic material caused by the compression thereof, its deformation takes place in a space of decreasing section 55 and the natural resistance, being offered by the material to these displacements while being guided in the direction of the decreasing section, is completed by a resistance which may be termed supplementary. In accordance with this invention, this supplementary resistance may be effected in various ways, namely, by thrust; by the pressure of a liquid enclosed in a cylinder of adjustable volume or by the controllable pressure of a gas. This 60 supplementary resistance may also be brought about by the considerable conicity of the elongating punches or dies.

The performance of the various phases of executing an assembly, involving two nested 70 metal shells and the interpositioning of a highly compressed elastic connecting element, is described in the following specification in which the reference characters denote corresponding parts in the accompanying 75 drawings.

Referring to the drawings, Figure 1 is a substantially longitudinal sectional view of an apparatus for effecting an assembly of the inner element within the outer element in 80 which the elastic substance has already been arranged; Figure 2 is a substantially longitudinal sectional view of an apparatus for assembling the inner element carrying the elastic connecting substance within the outer 85 element; Figure 3 is a longitudinal sectional view of the step which involves the assembly of the elastic substance within the outer element prior to the performance of the complete assembly shown in Figure 1; and 90

Figure 4 is a substantially longitudinal sectional view of a means for effecting in a single operation the steps practiced separately in the devices illustrated in Figures 1 and 3.

5 Referring to the drawings and particularly to Figure 1, 2 denotes the outer shell of the device and 3 the inner member which is to be introduced into the outer shell 2. In this embodiment, a connecting sleeve 4 of elastic material has first been introduced into the outer sleeve 2 and due to compression which has taken place in the latter in order to arrange it in the outer shell, the sleeve and the shell are closely adhered together by means 10 of friction. The inner member 3 is then inserted in the sleeve 4 and the step is carried out by placing a cone-shaped tip or punch 5 on the end of the inner member so that when the latter and the tip 5 are driven 15 into the elastic sleeve 4 in the direction of the arrow X, there will occur an elongation of the sleeve which, unable to compress any further, will extend longitudinally along the outer shell 2 until it has reached a length 20 where its bore admits the inner member 3. The inner member 3 is virtually a tube and the tip 5 is held in position by a shank 5^a which fits in the bore of the tube. The space limited by the interior surface of the element 2 and by the contour of punch 5, shows normally in the direction of the sinking, some decreasing sections in a direction opposite to that of the center punch. During the elongation, the material of the sleeve 4 could, 25 without the intervention of supplementary devices, expand in both directions, although the natural resistance, due to the shape of the space, is larger for the movement against the conicity of the punch. In accordance 30 with the invention, the expansion in the direction opposite to the direction of the arrow X is prevented by the sufficient conicity of the punch 5. Also in accordance with the invention and in order to add an 35 additional resistance to the expansion toward the decreasing part, an annular part 6, hollowed at the outer diameter of member 3, is made integral with the element 2 by means of hooks 2^a connected with the member 2 and capable of maintaining the part 6 in its position, in spite of the pressing from within the sleeve 4. As a result, the expansion of the sleeve 4 in the direction opposite to that indicated by the arrow X, is stopped, 40 beginning from a point selected at will and in accordance with the form given to the part 6.

In accordance with Figure 2 the sleeve 4 which has previously been set on the position 60 in member 3 and is adhering more or less strongly to it, is introduced by force into the element 2 by means of a part 7, which takes the form of a funnel. The free space between the internal face of the part 7 and the contour of part 3 offers, in the direction of

displacement of the part 3, towards its final position, decreasing sections. In order to prevent any sliding of the sleeve 4 on the inner element 3 a pressure of gas or liquid may be utilized in the chamber 3^a provided, for this purpose, with conduit 3^b. Part 3 is pushed by means of a piston 3^b traveling through a proper packing in the end of the cylinder 3^a. During the elongation produced by the displacement of member 3 and of the sleeve 4, in the direction of the arrow Y, the material of the sleeve can expand more easily toward the rear than toward the front. In order to add an additional resistance to the expansion of the sleeve toward the front, in accordance with the invention, an annular part 8 is made integral, temporarily, with the part 3 at a point located in front of the sleeve and with respect to the direction of the arrow Y. It will be clear that this part 8 will play a similar rôle to that of part 6 in Figure 1. Possibly an identical effect to that of the thrust parts 6 and 8 producing the additional resistance, could be realized by the action of a deformable body, the deformation of which will be limited, for example by its play, in a controllable volume capacity.

In Figure 2, for example, one can, by means of a conduit 11, connect the inner volume limited by member 2, part 7 and wall 9, against which rests the said member 2, with a tank, not shown in the drawings, of controllable volume and containing a fluid, the compression of which may increase during the throw of member 3 and of sleeve 4, up to a certain determined extent, in order to prevent, starting from a certain point, the expansion of the matter of sleeve 4 in the direction of the arrow Y.

Figure 3 concerns the application of the process of the invention to the phase of manufacture by which the sleeve 4 is introduced in the member 2, prior to the operation of elongation, of which Figure 1 represents one phase. In accordance with this, Figure 3 shows a member 12, acting in the manner of a piston or plunger, which is able to compress the sleeve 4 in part 7 in order to introduce the sleeve into part 2.

In order to give the invention a practical form, the member 12 ends at its forward end in a part 12^a having the shape of a cone, the opening thereof being larger than that of the cone formed by the internal surface of the part 7. Thus the limited space between part 12^a and the internal face of part 7 shows decreasing sections along the inverse direction of arrow Z.

As the sleeve 4 plunges into the part 7 by displacement of the member 12, in the direction of the arrow Z, the sleeve 4 expands freely in the direction of this arrow, but it encounters, in the inverse direction, a certain resistance due to the decrease of the cubic area between part 12^a and part 7. In ac-

cordance with the inventive idea and in order to add, starting from a certain moment, an additional resistance, the part of the member 12, to which part 12^a is connected, constitutes a shoulder which prevents the expansion of the sleeve toward the rear and counter to the direction of the arrow Z.

In the device shown in Figure 4, the introduction of a sleeve 4 into the element 2, is accomplished by elongation of the latter and the introduction of element 3 in a single operation. The socket 5^a of punch 5 is inserted into the end of part 3, and the latter at its front end is provided with a part 5^b similar in shape and purpose with that of part 12^a of member 12 in Figure 3.

A tubular member 13 serving as a housing for the tube 3 and punch 5 is projected along with them simultaneously with the displacement, in the direction of arrow Z, of the plunger 14. The housing 13 is made rigid with the plunger 14 through a notch 14^a therein and the nose 15^a at the end of one of the arms of a double lever 15 pivoted on the housing 13. The housing 13 is provided with a shoulder 13^a which, with respect to part 5^b of the punch 5^a has the same purpose in view as that of the shoulder of the member 12 with respect to the part 12^a in Figure 3. Beginning with a certain point in the travel of plunger 14, the cam follower end of the second arm 15^b of the lever 15, encounters a stationary part of a cam 7^a which is integral with part 7, and which projects downwardly to cause the complete disengagement of the nose 15^a from the notch 14^a; thus bringing about a disconnection between part 13 and part 14.

The continued advance of notch 14^a in the direction of the arrow Z, causes by the displacement of part 2 and of punch 5, the elongation of the sleeve 4 in accordance with what has been stated with regard to Figure 1, the disengagement of the nose 15^a of the lever 15 taking place simultaneously with the part 13^a of flange 13 occupying with respect to element 2, the same position as part 6 of Figure 1, holds with respect to element 2. The flange 13 is locked in this position in order to resist the stresses due to the expansion of the elastic sleeve 4.

In order to carry out the locking operation, the action of the cam 7^a against the end 15^b of lever 15, causes a projecting part 15^a of the latter to engage in a notch 7^a cut in the projection of part 7. As a consequence, any displacement of part 13 in the direction inverse to that of arrow Z, tending to cause lever 15 to pivot in counter clockwise direction, is prevented because of the thrust against the part 13 at the end of arm 15^b of the lever 15. The disengagement of the projection 15^a after the operation is terminated, can, for example, be effected by a pivoting part 13 around the axis of punch 5.

Having now described my invention and

the manner in which the same is practiced, what I claim as new and desire to secure by Letters Patent is:

1. The herein described method of effecting a connection between two elements, which consists in compressing an elastic substance to thereby elongate it and interposing the substance between the two elements in the presence of a supplementary resisting substance exerting its pressure against the ends of the compressed elastic substance and under conditions which cause an initial displacement of the elastic substance longitudinally through a tapering path. 70

2. The herein described method of effecting a connection between two sleeves, which consists in compressing an elastic substance to thereby elongate it into frictional engagement with one of the sleeves, supplying a displaceable cushion at opposite ends of the elastic substance, and thereafter introducing the elastic substance through a tapered space leading to the other sleeve while displacing said cushions to control deformation of the elastic substance in a longitudinal direction. 80 85

3. A device for forming a joint consisting of two elements disposed one within the other and an elastic substance interposed between the two elements, comprising a cone shaped guide through which the elastic substance projects to enter one of the elements and a tapered end for the other element to lead the latter into the elastic substance, and means abutting the elastic substance and in which the tapered end and second element are projected towards and into the elastic substance with the movement of the means to project the substance through the cone shaped guide and into the first element. 90 95 100

4. A device for forming a joint, as claimed in claim 3, including means for locking the last means to move with the second element a predetermined distance towards the first element to introduce the elastic substance into the first element, and means for releasing said locking means to allow the second element to continue its movement into the elastic substance in the first element. 105 110

5. A device for assembling an elastic substance, which has been compressed and is consequently under elongation, between an inner and an outer element to form a joint, a cone shaped guide directing its smaller end into the outer element, a block having a chamber and passage opening into the outer element and containing a substance displaceable under movement of the elastic substance towards and into the outer element, a jacket forming a continuation of the larger end of the cone shaped guide and being supplied with a substance under pressure directed against the trailing end of the elastic substance which is compressed and in stretched condition about the inner element, and a plunger fitting the trailing end of the inner 115 120 125 130

element and guided into the jacket to displace the elastic substance along the cone shaped guide and into the outer element with the movement of the compressed substance in the block and jacket.

- 5 6. A device for assembling an elastic substance in a joint as claimed in claim 5, in which the leading end of the inner element is provided with a temporary head to restrain
10 the elastic substance from being projected off of the inner element.

In testimony whereof I affix my signature.
